UNITED STATES PATENT OFFICE.

NACE M. CLARK AND CHARLES E. HUBBACK, OF SANTA CLARA, CALIFORNIA.

CANDY-CUTTER.

1,355,893.

Specification of Letters Patent. Patented Oct. 19, 1920.

Application filed December 1, 1919. Serial No. 341,737.

To all whom it may concern:

Be it known that we, NACE M. CLARK and CHARLES E. HUBBACK, citizens of the United States, and residents of Santa Clara, 5 in the county of Santa Clara and State of California, have invented certain new and useful Improvements in Candy-Cutters, of which the following is a specification.

Our invention relates to a device for cutting strips of soft candy into parts, and it 10 is the object of our invention to provide a device of the character indicated that will quickly and accurately cut strips of plastic material into small parts of equal size, and 15 quickly and easily detach such of said parts as may adhere to the cutting blades. Further objects of our invention are to provide a device of the character indicated that will be light in weight, of few parts, easily 20 manipulated and cleaned, and highly efficient in its practical application.

In the drawing:

Figure 1 is an end elevation of our improved candy cutter.

25 Fig. 2 is a vertical sectional view through the device in a plane parallel to the end thereof with the several parts in closed relation to each other.

Fig. 3 is a vertical sectional view through 30 the device in a plane parallel to the end thereof with the several parts in open relation to each other.

Fig. 4 is a plan view of the under side of the stripper member.

35 Fig. 5 is a plan view of the under side of the cutter member.

Referring now more particularly to the drawing, 1 indicates a base or table member having a back member 2 rigidly mounted 40 thereon, the latter having a rabbet 3 formed in the front upper portion thereof and extending the full length thereof.

At 4 is shown the cutter member mounted on back 2 by means of hinges 5 and provided with a suitable handle 6 attached to the upper surface thereof. The lower surface or member 4 is provided with a rabbet 7 on its outer edge and extending entirely around the same. The under surface of 50 member 4 is fitted with a plurality of equally spaced and parallelly arranged blades 8 of sufficient width to just reach the surface of table 1 when member 4 is placed in a horizontal position as shown in Figs. 1 and 2.

At 9 is shown a frame adapted to fit into a rabbet 7 in member 4 and connected to

said member by means of hinges 10, the said hinges 10 being positioned on the edge thereof adjacent the hinges 5. Frame 9 is 60 provided with a plurality of plates 11, on its under side, parallelly disposed with relation to each other and positioned crosswise of frame 9 and spaced a distance apart to permit the passage of blades 8 therebetween. Frame 9 is also provided with a 65 knob or handle 12.

In operation, a suitably sized mass of fondant may be rolled into a strip of desired circumference and rolled back into 70 the position shown at 13 whereupon member 4 is brought down, the blades passing through the spaces between plates 11 and severing the said strip into many parts of 75 equal length. The method of hinging the several members is such that when this operation is performed the frame 9 is automatically seated in rabbet 7 in member 4, and the two members 4 and 9 are also seated in rabbet 3 in member 2, frame 9 80 consequently being held in a horizontal position. Upon raising member 4 the frame 9 may be held by knob 12 until blades 8 have been withdrawn through the spaces between plates 11, this operation effectively 85 removing any parts of the candy that may have adhered thereto.

It may now be seen that we have provided a cutter that is extremely compact in 90 form, can be readily and quickly manipulated, especially in conjunction with the forming table 1, and satisfactorily meets the requirements for which it is designed.

It is understood, of course, that changes 95 of form, construction and method of operation may be made within the scope of the appended claim.

We claim:

A candy cutter comprising a cutting table provided with a raised portion, said 100 raised portion having a rabbet formed therein along the upper edge thereof, a member carrying a plurality of blades hingedly mounted on said raised portion in operative relation to said table and engaging said rabbet and having a continuous peripheral rabbet formed on its under side, 105 and a stripper frame hingedly mounted on said blade carrying member and adapted to seat in the rabbet formed therein and to engage the rabbet formed in said raised portion. 110

NACE M. CLARK.
CHARLES E. HUBBACK.
